Filed June 8, 1970, Ser. No. 23,358

Term of patent 14 years

Int. Cl. D22—05

U.S. Cl. D22—27

FIG. 1 is a side elevational view of a fish lure showing my new design;

FIG. 2 is a plan view of the fish lure shown in FIG. 1; and

FIG. 3 is a sectional view taken approximately on the line 3—3 of FIG. 2.

The broken lines are for illustrative purposes only.

The stippled areas indicate the presence of color contrast.

I claim:

The ornamental design for a fish lure, substantially as shown and described.
